UNITED STATES PATENT OFFICE.

CHARLES C. CADDEN, OF CLEVELAND, OHIO.

TELEPHONE-TRANSMITTER.

SPECIFICATION forming part of Letters Patent No. 718,310, dated January 13, 1903.

Application filed September 8, 1902. Serial No. 122,548. (No model.)

To all whom it may concern:

Be it known that I, CHARLES C. CADDEN, a citizen of the United States, residing at Cleveland, in the county of Cuyahoga and State of Ohio, have invented a certain new and useful Improvement in Telephone-Transmitters, of which the following is a full, clear, concise, and exact description, reference being had to the accompanying drawings, forming a part of this specification.

My invention relates to telephone-transmitters, and has for its object the provision of an improved form of battery-transmitter employing comminuted carbon or equivalent material interposed between the electrodes.

The invention has for its particular object the provision of an improved form of casing or inclosure for the electrodes and for the comminuted material interposed between the electrodes, which is provided with improved structural adjuncts that will permit relative movement between the electrodes, so that the transmitter may well serve its purpose, while at the same time preventing improper displacement of the comminuted material. To this end I provide the chamber that has a cylindrical wall and two end walls, all of which walls are preferably rigid or sufficiently so as not to be responsive to the action of sound-waves. Through one of these walls a stem is projected, which stem carries upon its inner end an electrode that is thus within the casing and which is clamped at its outer end to the main transmitter-diaphragm. The other wall of the chamber is preferably in the form of a threaded plate having threaded engagement with the annular wall of the chamber, there being also provided in engagement with the annular wall of the chamber a distance-preserving ring, against which the threaded end wall may be screwed. This distancing maintains the required space between the electrodes, in which space the comminuted carbon is disposed.

In order that the electrode that is attached to the speaking-diaphragm may have relative movement with respect to the companion electrode, there is interposed between the electrode that is to be thus movable and the adjacent chamber-wall a yielding lining of fabric, which affords a springy packing that serves to maintain the space between the

movable electrode and the end wall through which the stem supporting the electrode is passed constantly filled to prevent the admission of the carbon particles to such space, this interposed cushion also constituting an insulation to prevent short-circuit between the electrodes. There is also interposed between the speaking-diaphragm and the end wall of the casing in immediate association with the movable electrode a spring-like medium which serves to maintain the movable electrode in engagement with the cushion upon the interior of the casing that separates the electrode from the said end wall.

I will explain my invention more fully by reference to the accompanying drawings, in which—

Figure 1 is a rear view of the transmitter, an inclosing casing being removed to reveal details of construction. Fig. 2 is a vertical sectional view through the axis of the transmitter, portions of the structure being shown in elevation. Fig. 3 is an enlarged sectional view of portions of the transmitter. Fig. 4 is a view of elements shown in Fig. 3 in separated relation. Fig. 5 is a view of the front of the chamber or casing.

Like parts are indicated by similar characters of reference throughout the different figures.

The general characteristics of the transmitter are those frequently found in similar structures, there being provided a usual form of mouthpiece *a*, that is secured within the front plate *b* of the instrument, a cap *c* being provided upon the rear of the plate *b* to inclose the transmitter parts. The plate *b* is provided with an annular recess in which is disposed a rubber ring *d*, the ring being folded, as indicated, so that the speaking-diaphragm *e* may be contained between the folds. A bridge-wall *f* is provided upon the plate *b*, this bridge-wall being U-shaped at its middle, so as to afford a space in which the electrode-chamber of the transmitter may be contained. This electrode-chamber of the transmitter comprises an annular wall *g*, an end wall *h* adjacent to the transmitter-diaphragm, and a second wall *i* adjacent to the bridge-piece.

In order that the speaking-diaphragm may be yieldingly maintained against its seat in the front plate *b*, there is interposed between

the diaphragm and the casing a spring-like medium. This spring-like medium is preferably of a composite nature, a portion being in the form of a spring-spider *l*, while the balance is preferably in the form of a disk of fabric *m*, the legs of the spider resting against the fabric *m*, while the middle portion of the spider engages the middle of the diaphragm. By means of this construction the speaking-diaphragm is maintained against its seat with the required pressure, which pressure, however, is not sufficiently great to overcome the action of sound-waves. The element of fabric *m* delicately permits the movement of the diaphragm in consonance with the sound-waves.

The front electrode is preferably of a composite construction, it being formed of a metal disk *n*, which supports a carbon plate or disk *o*. The metal plate *n* is provided with a stem *p*, which passes through the wall *h*, through the fabric *m*, the spring *l*, and the speaking-diaphragm *e*. The stem is shouldered, the large portion of the stem engaging the spring *l*, while the reduced portion is threaded and passes through the spring *l* and the diaphragm, a nut *q* serving to hold the stem, the diaphragm, and the spring in combination. The rear electrode is also a composite structure, the rear wall *i* constituting a portion of the electrode, which rear wall carries a carbon disk *r*.

For the purpose of readily removing the parts of the transmitter the end wall *h* is preferably separately formed from the cylindrical wall *g*, which cylindrical wall is provided with an annular lip at its front portion, upon the rear of which lip the end wall *h* is engaged, there being provided a follower-ring *s*, which has threaded engagement with the annular wall of the casing for the purpose of maintaining the end wall in position. This follower-ring *s* also acts as a distance-preserving means, forming a shoulder upon the interior of the cylindrical wall against which the wall *i* is screwed. By being threaded the ring *s* may act as an adjustable distance-preserving agency, whereby the distance between the electrodes may be varied. When the follower-ring is to act as an adjusting-ring to regulate the distance between the electrodes, the front end wall of the casing is preferably soldered to the cylindrical wall or otherwise secured thereto.

55 There is interposed between the electrodes comminuted material *t*, as carbon, and in order to prevent a short-circuit about the comminuted carbon the ring *s* is provided with insulating-lining *u*, while an insulating layer *v*, preferably of fabric, which fabric is preferably woven, is interposed between the front wall *h* and the plate *n*. This fabric constitutes a yielding spring-like insulating element, which permits motion of the front electrode without allowing comminuted material to pass to the rear of the front electrode.

While I have herein shown and particularly

described the preferred embodiment of my invention, I do not wish to limit myself to the precise construction and arrangement herein shown; but,

Having thus described my invention, I claim as new and desire to secure by Letters Patent—

1. In a transmitter, the combination with the speaking-diaphragm thereof, of an electrode attached thereto, an electrode-chamber in which the said electrode is movable, and a yielding medium interposed between the chamber and the speaking-diaphragm, substantially as described.

2. In a transmitter, the combination with the speaking-diaphragm thereof, of an electrode attached thereto, an electrode-chamber in which the said electrode is movable, and a yielding medium interposed between the chamber and the speaking-diaphragm, the said yielding medium including a spring in engagement with the diaphragm and the chamber, substantially as described.

3. In a transmitter, the combination with the speaking-diaphragm thereof, of an electrode attached thereto, an electrode-chamber in which the said electrode is movable, and a yielding medium interposed between the chamber and the speaking-diaphragm, said yielding medium including fabric in engagement with the chamber and the diaphragm, substantially as described.

4. In a transmitter, the combination with the speaking-diaphragm thereof, of an electrode attached thereto, an electrode-chamber in which the said electrode is movable, and a yielding medium interposed between the chamber and the speaking-diaphragm, said yielding medium including a spring and fabric for forming engagement between the diaphragm and the chamber, substantially as described.

5. In a transmitter, the combination with the speaking-diaphragm thereof, of an electrode attached thereto, an electrode-chamber in which the said electrode is disposed, said electrode-chamber including a substantially rigid wall interposed between the electrode and the diaphragm, and a yielding distance-preserving medium upon the interior of the chamber interposed between the electrode and the said substantially rigid wall, substantially as described.

6. In a transmitter, the combination with the speaking-diaphragm thereof, of an electrode attached thereto, an electrode-chamber in which the said electrode is disposed, said electrode-chamber including a substantially rigid wall interposed between the electrode and the diaphragm, and a yielding distance-preserving medium upon the interior of the chamber interposed between the electrode and the said substantially rigid wall, the said medium being in form of a fabric, substantially as described.

7. In a transmitter, the combination with the transmitter-chamber of electrodes therein,

and the follower-ring within the chamber serving by its adjustment to engage one of the electrodes and thereby secure the adjustment of the distance between this electrode and the companion electrode, substantially as described.

8. In a transmitter, the combination with the two electrodes thereof, of a chamber for containing the same, including an end wall separately formed, and an annular chamber, in the interior of which said end wall is disposed, said annular chamber being provided with a shoulder for defining the position of said wall, said chamber also including an annular wall threaded upon its interior, a fol-

lower-ring having threaded engagement with the annular wall serving to clamp the said end wall in place, and a threaded plate *i* having engagement with the annular wall and limited in its movement by the follower-ring, ²⁰ the said threaded plate carrying an electrode, substantially as described.

In witness whereof I have hereunto subscribed my name this 4th day of September, A. D. 1902.

CHARLES C. CADDEN.
